RDP D-Style Drip Edge (1.25"×4"×5', Black), available in Amazon.com, date first available Feb. 26, 2022[online], [site visited Jul. 8, 2024], Available from the internet URL: <https://www.amazon.com/D-Style-Drip-Edge-1-25-Black/dp/B09TFYB153?th=1> (Year: 2022).*

Primary Examiner — George J Ulsh*Assistant Examiner* — Kathryn Elizabeth Zieno(74) *Attorney, Agent, or Firm* — Sanchelima & Associates, P.A.; Jesus Sanchelima; Christian Sanchelima(57) **CLAIM**

The ornamental design for a gutter drip edge flashing as shown and described.

DESCRIPTION

FIG. 1 is an isometric view of a gutter drip edge flashing showing my new design;

FIG. 2 is a front elevational view thereof;

FIG. 3 is a top plan view thereof;

FIG. 4 is a bottom plan view thereof;

FIG. 5 is a right elevational view thereof;

FIG. 6 is a left side elevational view thereof; and,

FIG. 7 is a rear elevational view thereof showing my design.

1 Claim, 3 Drawing Sheets(56)
